WIDE BAND ANTENNA

Nils E. Lindenblad, Port Jefferson, N. Y., assignor
to Radio Corporation of America, a corporation
of Delaware

Application May 18, 1938, Serial No. 208,573

54 Claims. (Cl. 250—33)

This invention relates to a short wave antenna. An object of this invention is to provide an antenna suitable for the transmission of an extremely wide band of frequencies. My antenna is, accordingly, especially suitable for the transmission of high quality television signals.

Another object of this invention is to provide a practical radiator having a substantially flat characteristic over a wide range of frequencies making it thereby especially suited for television 10 transmission.

Another object of this invention is to provide an antenna adapted to transmit, with relatively low and relatively constant circuit loss over a wide range of frequencies horizontally polarized 15 waves.

A further object of this invention is to provide an antenna having a low factor of reflection over a wide band of frequencies.

Still a further object of this invention is to provide an antenna having the above characteristics and which, in addition, shall be mechanically safe and suitable for use on tall buildings or towers.

A further object of this invention is to provide 25 an antenna which will be simple, mechanically strong, and entirely metallic in construction.

Still another object of this invention is to provide an antenna which will be entirely electrically grounded for protection against lightning, and which, though grounded, will not have its operation as an effective and efficient high frequency 30 antenna, impaired or otherwise affected.

Briefly, this invention comprises an antenna comprising one or more conductors having a diameter which is a large fraction of the length of the working wave. As an example, in accordance with this invention conductors having a diameter of from 15 centimeters (maximum diameter of one component) to 26 centimeters 40 (maximum of the other component) have been used. In some of the modified forms of this invention the diameter of the antenna, as a whole, is arranged to decrease with an increase in distance from the neutral voltage planes of the 45 antenna.

The antenna as constructed according to one form of this invention, is connected to the associated apparatus by means of a concentric transmission line, the transmission line being gradually expanded to make a smooth transition between the comparatively small diameter transmission line and the large diameter antenna components. The ratio between the diameters of the inner and outer conductors of the transmission 50

line is kept constant in the transition section in order to prevent any material change in the characteristic line surge impedance.

In order to maintain a constant ratio of resistance to low reactance in one modification this antenna is arranged so that the shell of the concentric transmission line connected thereto comprises a portion of the radiator with the enlarged central conductor as the other portion. The integrated length of the combination is in the order of a quarter of the operating wave length.

The antenna, as a whole, is preferably fed at the transition point between the sleeve and the central extension portion of each quarter wave radiating section. This makes the sleeve portion of the antenna a parallel reactance of predominant inductive value and the center conductor extension a series reactance of predominant capacitive value.

By electrically connecting a predetermined portion of the center conductor extension to the shell portion some irregularities in phase relationship between the different portions of the antenna are avoided and metallic grounding of the entire antenna is permissible. In order to compensate for the shunting inductance caused by this connection a compensating shunt capacity may be provided. One way this may be done is by decreasing the ratio between the diameters of the outer and inner conductors of the transmission line along the length of the tapered transitional portion between the transmission line proper and the antenna.

The foregoing principles of this invention may be applied to a turnstile antenna having a plurality of horizontal quarter wave sections arranged around a central point and mechanically and electrically connected at the center. 40 These radiators may be energized in the proper phase relationship to generate a rotating electrical field, as disclosed in Patent No. 2,086,976, issued to G. H. Brown, July 13, 1937. Also, a plurality of turnstiles may be arranged one above the other and energized by different signals. According to this aspect of this invention opposite phase rotation between the successive turnstiles may be provided in order to reduce coupling therebetween.

Furthermore, a turnstile and a loop antenna are provided arranged in parallel horizontal planes with their axes on a common perpendicular axis. The loop antenna may be constructed of a plurality of folded dipole sections bent into a circle.

A more complete understanding of this invention may be had by references to the following detailed description and the accompanying drawings. In the latter, Figures 1, 3, 5, 7, 8, 10, 12, 14, 15, 16 and 18 illustrate different forms of this invention and Figures 2, 4, 6, 9, 11, 13 and 23 are curves explanatory of the characteristics of antennas constructed according to this invention. Figure 17 is a diagram showing the instantaneous current relationships between two portions of a turnstile antenna connected according to this invention. Figures 19 and 20 are figures further illustrative and explanatory of the principles of this invention, while Figures 21 and 22 show preferred connections for connecting the antenna to the transmitter. Figures 24 and 25 illustrate diagrammatically the method of connecting a plurality of video and audio transmitters to a single antenna of the invention. Figures 26 and 27 illustrate further modifications of the invention.

Referring to Figure 1, reference numeral 11 indicates the radiating portion of a quarter wave antenna so-called because its length is physically substantially equal to one-quarter of the length of the operating wave. Radiator 11 is fed by a concentric cable or transmission line comprising casing 13 and central conductor 14. The transmission line casing 13 is terminated at the base of the antenna and electrically connected to a grounded conducting surface, body, or sheet, 12, such as a metal roof or the steel framework of a building or tower. The conductor 11 is of substantially larger diameter than is customary in the prior art. In one embodiment which is used with a wavelength of the operating wave of the order of 175 centimeters, the diameter was of the order of one inch. The surge impedance of the transmission line is preferably made of the order of 36 ohms which is the theoretically expected impedance at the base of a quarter wave radiator.

In determining the reflection of this antenna and plotting the reflection factor against the frequencies, curve *a* in Figure 2 is obtained. This reflection factor is measured on the transmission line and is derived from the ratio between the maximum and minimum current appearing at different points along the transmission line. In short, this factor is the ratio of a current node to antinode as measured along the line. Reflection may be caused in several ways. First, the loading resistance may not correspond to the surge impedance of the line feeding it; second, the loading impedance may be correct but a reactive component may be present; third, both these causes may be combined. The quantity and kind of reflection present is determined from the position of maxima or minima of the standing wave component on the line. If it is desired to obtain an expression of the reflection in percentage terms, taking a specific example where the ratio of maximum to minimum voltage is 1.1 to 1, the percentage reflection is obtained from the following expression:

$$\% \text{ reflection} = \frac{1.1 - 1}{1.1 + 1} = \frac{0.1}{2.1} = 4.76\%$$

The figures appearing vertically along the left-hand side of Figure 2 have been expressed directly as the ratio of maximum to minimum voltage and not as percentages.

Using a smaller conductor for radiator 11, $\frac{5}{8}$

of an inch for example, curve *b* of Figure 2 is obtained. As can readily be seen, while neither of these radiators presents a perfect impedance match to the transmission line, the larger diameter radiator has a wider effective band width than the other.

Modifying the radiator, as shown in Figure 3, but using the same 36 ohm transmission line, by substituting a tapered radiator portion 21 enables obtaining a desirable impedance match for a rather restricted band of frequencies or wave lengths, as shown by the sharp minimum point of the curve in Figure 4. Therefore, while a good impedance match is obtained over a very narrow band of frequencies, the band width for this modification is not materially improved and will be found too narrow for a high quality, wide frequency band television transmission.

It therefore follows from the previous discussion that the method of energization of the antenna has a very important effect on the band width and it is to this problem that the remainder of this specification provides a highly satisfactory solution.

I have discovered that a radiator in which the shell of the transmission line forms an active part of the radiator itself offers a variety of advantages. The modification of this invention, constructed as in Figure 5 wherein the shell portion of the concentric transmission line is extended beyond the ground connection sheet 12 for a portion of the distance of the antenna, results in an improved frequency characteristic as shown in Figure 6. By using this construction a more perfect impedance match is obtained for much wider bands of frequencies, particularly when used in conjunction with the teachings of Figures 1 and 2 prescribing conductors of large diameters. The center radiator 31 in Figure 5 continuing beyond the shell has a series reactance characteristic of predominant capacitive value for the portion "B" while the lower portion "A" of this composite radiator formed by the outside of the projecting shell has a parallel reactance characteristic of inductive predominance. These two elements in series form a circuit having a wider or improved band width characteristic. As can be seen in Figure 6, the typical reflection curve is much broader and flatter over a wide range of frequencies $f-f'$ and has a small hump in the center. This hump is natural since it is the result of a combination of two effects which can only be perfect for definite frequencies.

In addition to the compensating advantages already mentioned, another and exceedingly important advantage is that by proportioning the center line and the sleeve extensions the antenna can be made to match any concentric line. For various diameters of conductor 31 the ratio between lengths A and B for optimum band width $f-f'$, that is, maximum band width with a low factor of reflection does not vary greatly for a given line or matching impedance. Over a range of line impedances varying from 70 to 145 ohms it appears that a line impedance of 110 ohms may well be chosen as giving very satisfactory band width. For constant radiator diameters the ratio between lengths A and B (Figure 5) increases as the line impedance is increased. However, that is not the only factor which influences the length of A and B (Figure 5) since this ratio can be modified if the external dimensions and shapes of the conductors 31 and 33 are correspondingly altered. The aim is to approach a combination

of the capacitative effect of conductor 31 and inductive effect of shell 33 such that the

$$\sqrt{\frac{L}{C}} = R$$

for as wide a frequency band as possible. In the foregoing equation L represents the inductance of shell 33, C the capacity of conductor 31 and R indicates the radiation resistance for each radiating component of the antenna.

Throughout the description where the line impedance is mentioned this value has been obtained by the use of the formula

$$Z = 138 \log_{10} \left(\frac{D}{d} \right)$$

where D is the inner diameter of the outer tube 33 and d is the outer diameter of the inner conductor 14 of the concentric line.

It is also desirable to make the antenna elements of larger diameter than the transmission line elements of which they are an extension. A most convenient way in which the radiator of large diameter and the central conductor of smaller diameter of the transmission line may be connected is by means of a tapering portion, such as portion 42, 43 as shown in Figure 7, or it may be continuously curved as in a horn following an exponential, ellipsoidal or other curved law. The interior surface of the expanding portion when a curved expanding section is used may be that generated by rotating an ellipse about an exterior axis parallel to the major axis of the ellipse. The latter shape has been found to be more advantageous since it permits a smoother continuation into the ellipsoid shape of the extended central conductor. It also permits a smooth rolling over of the sleeve into an ellipsoidal external shape for the lower section of the radiator.

Figure 8 illustrates an antenna constructed according to the foregoing. In this form of the invention an ellipsoidal expansion 51 for the central conductor 14 of the concentric line has been used. The maximum diameter of the expansion 51 was 8 centimeters. The overall length of the antenna was 55.5 centimeters or approximately .28 wave-length long. The outer conductor 13 is flared conically or tapered at its inner surface near the antenna, as shown by reference numeral 52, the exposed portion 53 thereof being cylindrical, about 15 centimeters in diameter and 24 centimeters long. Also, conductor 14 is gradually expanded to a wider diameter 42 near the elliptical antenna 51.

In this form of the antenna a concentric transmission line has been used in which the inner diameter of the outer conductor 13 was 2 inches and the outer diameter of the inner conductor 14 was $\frac{1}{8}$ of an inch which corresponds to a line surge impedance of 110 ohms.

As can be seen by reference to the curves in Figure 9, the modification shown in Figure 8 has a flat characteristic over an even wider frequency range than the arrangement of Figure 5, which was shown in Figure 6.

Referring, now, to Figure 10, which shows a further modification of the invention, I have discovered that the addition of a metal conductor 54 between the ellipsoidal radiator and the shell 53 is very beneficial. Without this connection the phase relation between the extended portion 51 and the shell 53 has sometimes too much freedom so that some irregularities in the impedance may occur within the desired operating frequency band. This connection also is of great

importance in that it permits of a metallic grounding of all parts of the antenna as regards direct current voltages, lightning strokes, etc., and has an additional mechanical benefit in that

5 it aids in supporting or guying the somewhat expanded curved conductor 51 rigidly in position. As shown in this figure, the shell portion 53 is also made of a curved cross section 52, 53 which has been found to be beneficial. The shell 52, 10 53 is somewhat in the form of a half toroid, the toroid being formed by revolving an ellipse about an exterior axis parallel to the major axis of the ellipse. The lower half is replaced by a metal base or frustum of a cone 1012.

15 The curve in Figure 11 shows the further band width improvement obtained by increasing the diameter of the extension portion 51 to 12 centimeters and approaching a condition where

$$\sqrt{\frac{L}{C}} = R$$

The length of 53 was 24 centimeters and the diameter was increased to 26 centimeters.

As shown in Figure 12 and in the accompanying 25 curve in Figure 13, it has been found further improvement was effected by the further increase in dimensions resulting in a more perfect fulfillment of the dual requirements of providing a ratio of

$$\sqrt{\frac{L}{C}}$$

30 which is constant over as wide a frequency band as possible and also a maximum compensation 35 between capacitive member 51 and inductive member 53. A metal fin 55 of substantial size and cross sectional area was added to provide mechanical support for radiator 51. A substantial fin is more easily compensated for by increased dimensions of the system. This fin may be either solid or hollow as desired from a mechanical standpoint. Preferably, it is somewhat circular in cross section at its center portion gradually fairing smoothly into the ellipsoid 51 and the side of the grounded metal shell 53.

40 From another viewpoint, the introduction of this fin 55 also has the following effect which should be noted. It constitutes a shunting or parallel current path and thus increases the 45 impedance of the antenna looking into the feed line. This shunt is inductive. One way in which this may be compensated for is by increasing the length of the ellipsoidal extension portion 51. However, as this may result in too much deviation 50 from established proportions a more satisfactory way of compensation is by lowering the surge impedance of the line at and towards the mouth of the internally horn-shaped sleeve 52. This is accomplished by decreasing the ratio of

55 the inner diameter of the outer conductor to the outer diameter of the inner conductor along the 60 length of the transitional portion or tapered section. This results in a decrease of the surge impedance along the length of the expanding 65 portion and the resultant capacity compensates for the increase in inductance caused by fin 55.

Also for adjustment purposes, the fin 55 and antenna 51 may be provided with cylindrical telescoping sections at their central positions and 70 when desired adjustment is reached the parts may be fastened rigidly together by means of set screws, soldering brazing, etc.

In the embodiment shown in Figure 12 and which, upon test had a further improved characteristic as shown by the curve of Figure 13, a

center conductor extension 51 has been used having a diameter of 15 centimeters and an overall length of 60 centimeters. The diameter of shell 53 at the top was 18 centimeters between horizontal portions at the extreme top. The diameter at the base was 26 centimeters. The fin 55 was 10 centimeters long between the nearest points of attachment to the ellipsoid and shell and had a diameter of $\frac{1}{10}$ of a centimeter.

Figure 14 illustrates, partly in cross section, another modification of the invention of Figure 12 in which a larger diameter ellipsoidal central radiator 51 and two supporting fins 55 are used. The minor axis of the ellipsoid 51 in this form is 27 centimeters long and the shell portion 53 was made hemispherical in form. The shell portion 53 in this modification forms with its image, due to ground sheet 12 effectively a half wave radiator. Auxiliary half horns 52' were provided in this form in order to make the antenna, with its image, the electrical equivalent of a four arm turnstile which will be later described. The proportions of this form proved to have passed the optimum values satisfying the desired conditions already set forth. Even an increase of the diameter of 51 of Figure 12 from 15 to 18 centimeters proved to be in excess of the optimum dimensions although to a lesser degree than Figure 14. The dimensions of Figure 12 seem to be about the optimum for the frequency band used in the tests. It is, of course, possible that another line of attack may produce an even more perfect dimensional relationship resulting in a still wider band.

In each of the forms of this invention shown in the preceding Figures 8 to 14, the ellipsoidal portion may be either solid or hollow, as desired.

The outer conducting surfaces of the ellipsoids constitute the only portions which are substantially active or effective for transmitting waves or receiving them. A convenient and useful form of construction is to cover a wooden form of the desired shape with a thin copper foil soldered to form a continuous sheet over the entire surface.

Figure 15 illustrates the application of the elementary form of turnstile antenna shown in Figure 14 to a complete turnstile. A central substantially spherical metal portion 53 is supported on a metal pedestal 56 containing the transmission line. Within the central portion 53 are four inwardly flared sockets forming effectively horizontal horn units 52 whose axes point horizontally in four directions. Within each of these units 52 and extending outwardly therefrom is a radiating portion 51. Each opposing pair of radiating elements 51 with the central portion 53 constitutes a single half wave antenna. Opposite members of the pairs of radiators 51 are excited in phase opposition and adjacent members in phase quadrature. A rotating field is thus obtained. The structure for obtaining this phase relationship will be later discussed and more fully disclosed in subsequent figures.

In order to suppress somewhat the vertical radiation from the antenna the supporting column 56 should be half the length of the operating wavelength in length between the center of the antenna system, as shown, and the metal surface 12 forming the top of the frustum of a metal cone 1500 which may be the top of a tall building.

In order to avoid the complications of a cross coupling filter which is necessary when using only a single antenna for both the audio and

video transmission, independent antennas for each signal are used. If these are to be located in proximity to one another they have to be so designed and located that no cross coupling occurs. In this figure is shown a second antenna for the audio signal on the same axis as the first described antenna system 51, 52, 53, 54, and utilizing radiating members 61 within and extending from shells 63. These radiating elements are arranged to operate as a second antenna connected similarly and radiating a rotating field in the same way as above described. Preferably, the direction of rotation of this field is made opposite to that of the one radiated by the upper antenna in order to reduce coupling between the two antenna systems. As before, guying conductors or fins 54, two for each antenna element, are provided for stability and grounding of the antennas for lightning strokes.

In a practical embodiment of this modification which would probably be located in an exposed site, such as at the top of a tall tower or building, such as the Empire State Building, New York City, aviation warning lights 65 and weather instruments 66 could conveniently be mounted at the top of the antenna structure on an extension of pedestal 56. These instruments are, of course, at a neutral or zero potential as far as radio frequency energy is concerned.

While a four arm antenna arrangement in this figure is shown, it is within the scope of this invention to use any number N arms 51, if necessary, in which case the phase relation of the voltages between consecutive arms 51 will be

$$\frac{360^\circ}{N}$$

The modification of this invention shown in Figure 16 is similar to that of Figure 15, except that the relative positions of the two antenna portions 51, 51 and 61, 61 have been reversed and both are supported on a supporting column 56'. In this form of construction it is simpler to obtain a circular radiation pattern in the horizontal plane for a pair of antenna due to the fact that the radiating portions of each antenna system are much more closely spaced and less difficulty is had in obtaining the proper space and phase relation between the consecutive radiating portions. Undesired interference patterns are thus readily avoided. If desired, the two antenna systems may be turned at an angle of 45 degrees with one another on their common axis to further decrease any possible coupling between the two antenna systems. The main uncoupling is, however, provided by the off phase rotation of the antennas.

Since the extreme band width provided by the turnstile antenna is not in all cases necessary, especially for transmitting audio signals, and in order to further decrease any possibility of coupling between the audio and video antennas, a loop and a turnstile located, as already suggested for two turnstiles in Figure 16, constitute a further improvement in that these forms of antennae are inherently entirely uncoupled at all frequencies, as will be explained by reference to Figure 17. This diagram illustrates the current X at any given instant in a loop with respect to the currents, indicated by Y, at the same instant obtaining in a turnstile antenna coaxially mounted with respect to the loop. It will be obvious on inspection of the figure that the two antennas are inherently perfectly uncoupled. Since any diametrical conductor is in a neutral

position with regard to the field set up by the loop and a turnstile mounted on the axis of the loop has such a position, there will be no coupling between the two antennas.

A modification of this invention utilizing this principle is shown in Figure 18.

In this figure the turnstile antenna is shown at 51, 53. Each element 51 is constructed, as has already been described with reference to Figures 15 and 16, but with closer adherence to optimum proportions as shown in Figure 12. As pointed out before, the optimum dimensions seemingly prevent the use of a spherical hub and in this modification a cross shaped hub, formed by the elements 53, is used. The audio antenna 70, 71, 72, which is substituted for the antenna 61, 61 shown in Figure 16, comprises four folded dipole sections bent into a circular form, as shown somewhat more clearly in Figure 20. The principle of this antenna will be more clearly understood by reference to Figure 19.

Figure 19 discloses a folded dipole having a pair of conductors 70, 71, which are mechanically arranged in parallel planes, conductor 71 being broken at the center and the two wire transmission line Z connected at that point impressing alternating voltages of opposite instantaneous polarity at points e and f. When the length from e to g and from f to g is half a wave in length, branches 71 and 70 may be considered in parallel, that is, they have a common voltage at ends 72 and are in phase. The impedance between e and f is then approximately four times that of a conventional dipole which has a transmission line inserted at its mid point, or about 288 ohms. A folded dipole of lesser dimensions may also be obtained if the distance from e to g and from f to g is a quarter wave in length. Under this condition the voltage, instead of being a maximum at 72, builds up from point g along the length of the conductor toward point f so that a maximum voltage exists between e and f. This corresponds to a very high feed impedance between e and f to transmission line Z. The currents in 71 and 70 are now to a considerable extent in opposite directions but since they are not of equal magnitude a resultant field is obtained which causes radiation. Although in this elementary form the dipole provides a feed impedance which is impractical its lesser dimensions are very attractive in connection with this particular location, near the video antenna 51, 53. Tests show that when combining these elements of high feed impedance into a four section circular array, as shown in Figure 20, a mutual effect between the ends 72 of adjacent dipoles was obtained, which substantially lowered the feed impedance between e and f so that it became possible to feed the system with lines of practical dimensions. The resultant impedance due to the mutual reactance of ends 72 is in the order of 220 ohms. As already mentioned, the doublets being shortened to $\frac{1}{4}$ wave in length results in a smaller diameter loop with less chance of coupling between the loop and the turnstile antenna. In the actual case there is some deviation from the exact figure of $\frac{1}{4}$ of a wave. The actual length is determined empirically and is much closer to an eighth than to a quarter wave.

Figure 20 shows the way in which the four bent folded dipole antennae are connected to the transmission line. Each of leads 75 from the dipoles are connected together to the outer conductor of concentric cable transmission line 73.

13, each of leads 76 are connected together to the central conductor of transmission line 73. In this way a phase difference of 180 degrees is obtained between conductor 75 and conductor 76. The impedance of each of the folded doublets 70, 71 is in the order of 220 ohms and when these are connected in parallel to transmission line 73 their effective impedance is in the order of 55 ohms which forms a proper impedance match with the transmission line actually used. At the mid or voltage nodal points g (Figure 19) metal supporting rods 80 are provided which are fixed and directly connected to the grounded outer shell 77 (Figure 21) thereby supporting the dipoles without affecting their radio frequency operation and simultaneously providing a low resistance ground for lightning strokes. Inside of pedestal 56 supporting the audio antenna 70, 71 at a distance equal to one-quarter of the length of the audio carrier wave below the point of attachment of the antenna to transmission line 73, the transmission line is connected to the interior of the pedestal by a conductor 77. The quarter wave loop thus formed electrically liberates the top edge of the shell of transmission line 73 by the principle of extremely high impedance at this point caused by connection 77 a quarter wave back. Although transmission line 73 is originally nonsymmetric to push-pull load, it can now center itself to such loading. The perfection of the centering depends upon how perfect the load is centered or balanced around a neutral which in this case is provided by support 80.

35 Fig. 21 shows in more detail the connections of both the audio loop and the video turnstile to the transmission lines. This figure is partly in section and shows the connection loop for obtaining the 90 degree phase relationship between two adjacent arms of the turnstile video antenna. In order to prevent confusion the other loop which connects to the remaining two arms of the turnstile has not been shown but is exactly similar to the one shown. As can be seen, the central conductor 14 of the concentric conductor transmission line is connected to the left hand ellipsoidal radiating portion 51 of the turnstile while the other conductor 13 is connected to the end of the tapered portion which attaches to the shell. 40 This transmission line is continued downward a convenient distance and turned back on itself at 81 and connected to the next adjacent arm of the turnstile, extending away and in back of the plane of the drawing. To one side of the loop 13, 14, 81, thus formed is connected the concentric cable transmission line 13' having an interior conductor 14' at such point that the distance from the point of attachment to one arm of the turnstile is exactly $\frac{1}{4}$ of the length of the operating wave longer than the distance to the adjacent arm of the turnstile. This provides the necessary 90 degree phase relationship between the two adjacent arms and has another and further advantage when the line is properly matched. In the case of such a transmission line if either a capacitive or an inductive reactance, which is fairly high compared to the surge impedance of the line, is added across the transmission line, its reactance may be perfectly compensated for by the addition of another and exactly equal reactance at a spacing of an odd multiple of a quarter wave therefrom. Thus, in the antenna, any residual reactance in one arm of the turnstile is exactly compensated for by a similar reactance of the next adjacent arm of the

turnstile to which it is connected through the phasing loop.

The application of this principle, as shown in Figure 21, increases the band width antenna of the turnstile elements which have the already exceptional band width of approximately 20% with a reflection of 5% or less to approximately 30% with the same amount of reflection. At the point of attachment of concentric cable 13', 14' to the phasing loop 13, 14 a slightly enlarged portion 18 is provided on the inner conductor 14. This is to compensate for the change in impedance in the transmission line due to the aperture in casing 13 where casing 13' is attached and through which conductor 14' passes. The transmission line 13', 14' is fed by one phase. The other two arms of the turnstile are connected in an exactly similar manner and are fed by the opposite phase of the video transmitter. Of course, it is to be understood that line 13', 14' must have a surge impedance half that of 13, 14.

As shown in Figure 21, additional support for radiator 51 is supplied by means of insulator 59 in the throat of the expansion portion of the antenna. In order to prevent rain, snow, etc., from running into the expansion a horn portion, a semicircular rainshield 57 is attached to the top of shell 53 and immediately behind it and attached to the radiator 51 is an annular shield 58. These two shields 57 and 58 are formed of insulating material. If desired, electric heating elements may be incorporated within radiators 51, arms 55' and the shell 53 in order to melt accumulations of sleet in severe weather.

Figure 22 shows diagrammatically the complete connection of all four arms of the turnstile antenna to the push-pull output of the video transmitter. In order to simplify the disclosure the outer shells of the transmission lines have not been shown.

By changing both transmission lines 13', 14' to a position diametrically opposite on the phasing loops, as indicated by R, R (Figure 22), the phase rotation field produced by the antenna may be reversed.

Figure 23 illustrates curves showing the extreme band width obtained with the turnstile antenna 51, 53 constructed according to Figure 18. These curves were taken using a reference wave length of 225 centimeters. The curve in solid lines was made when my antenna was first constructed and the curve in dotted lines illustrates the improvement obtained after correcting the transmission line to match the antenna more perfectly. Some of the other important dimensions of the antenna used, whose characteristic is shown by the curve of Figure 23, are as follows: The length of the minor axis of the ellipsoid 51 was 15 centimeters. The length of the major axis of each of the ellipsoids 51 was 41 centimeters. The diameter of the shell portions at their extreme ends was 18 centimeters, and the maximum diameter of portion 53 was 26 centimeters. The length from the center of the hub to the end of 53 was 29 centimeters. Using the modified form of the supporting member, as shown by 55' in Figure 18, in order to obtain maximum mechanical strength and retain the desirable electrical features, the maximum diameter of the supporting arm was increased to 1.3 centimeters at its central portion and about $\frac{1}{6}$ of a centimeter in each of the stirrup portions 55''. The arm 55'' was attached to each ellipsoid 17 centimeters from the end of shell 53

while the point of attachment of the arm to shell 53 was 8 centimeters in from the end of the shell.

As can be seen by an inspection of the curve in Figure 23 the band width with less than 5% reflection is so broad that it is entirely feasible to transmit two complete television programs over a single antenna. This may be conveniently done by an arrangement as schematically shown by block diagrams in Figures 24 and 25. If it is desired to use only a single antenna, as shown in Figure 24, the first video transmitter 101 and its corresponding audio transmitter 102 are first fed separately into a separating filter 103 and there combined into a single channel 104. Likewise, the second video transmitter 201 and its corresponding audio transmitter 202 are fed separately into the separating filter 203 and there combined into a single channel 204. These two channels are then combined by filter 105 into a single channel 106 and applied to the single turnstile antenna. If it is desired to transmit the video signals over one antenna and the audio signals over the other, as in Figure 18, except that two complete programs are radiated, it may be done as in Figure 25, which shows the first audio transmitter 102 and the second audio transmitter 202 fed into a filter 213 and thence to the audio antenna 70, 71. At the same time the first video transmitter 101 and the second video transmitter 201 have their outputs combined in the filter 113 and the combined output is applied to the video turnstile antenna 51, 53 of Figure 18.

Any of the antennas described may be used for receiving as well as for transmission.

Moreover, the turnstile antenna, as shown in Figures 15, 16, 18 and 21 may be combined with a vertically polarized antenna as shown in any of Figures 5 to 12, inclusive, mounted centrally thereabove. An antenna constructed according to this concept is shown in Figure 26. Since each part has been separately described in detail, it is believed unnecessary to describe the combination which should be clearly understood from an inspection of the figure.

Also, I may construct a plurality of half wave antennae according to the principles heretofore set forth and arrange them in a common horizontal plane about a central point and lying along tangents equidistantly spaced about a circle having its center at that point. The characteristics of an antenna having its radiating members thus arranged have been disclosed in my co-pending application No. 76,745, filed April 28, 1936, now Patent No. 2,131,108. The adaptation of the present antenna to such construction is shown in Figure 27.

Furthermore, any of the antennae or combinations thereof, heretofore described, may be mounted within a metal paraboloid at the focus thereof for directional signalling.

It should be clearly understood that the theory of operation outlined heretofore in this specification is given only by way of explanation and that while it is believed to be substantially accurate the invention is not dependent upon the absolute accuracy of the theory expressed but may also be practiced empirically from the finite values, also heretofore given.

It should also be clearly understood that while I have particularly shown and described several modifications of the invention, the invention is not to be limited thereby but may be modified

without departing from the spirit and scope thereof.

We claim:

1. An antenna system comprising a number N of radiating elements disposed radially about a central point in a common horizontal plane, each radiating element spaced substantially

$\frac{360}{N}$

degrees from adjacent radiating elements, each of said radiating element comprising a central conductor element having a transverse dimension which is a large fraction of the operating wave and an outer shell surrounding a portion of each of said conductors at their adjacent ends, said central conductor extending radially outward beyond the end of said outer shell, the over-all length of each of said radiating elements including the exposed portion of said central conductor and the over-all length of the shell being substantially equal to a quarter of the length of the operating wave, the capacitive reactance C of said exposed portion and the inductive reactance L of said shell portion being so related that

$$\sqrt{\frac{L}{C}}$$

as nearly as possible approaches R , the radiation resistance of each component of said antenna.

2. An antenna system comprising a number N of radiating elements disposed radially about a central point in a common horizontal plane, each radiating element spaced substantially

$\frac{360}{N}$

degrees from adjacent radiating elements, each of said radiating elements comprising a central conductor element having a transverse dimension which is a large fraction of the operating wave and an outer shell surrounding a portion of each of said conductors at their adjacent ends, said central conductor extending radially outward beyond the end of said outer shell, the over-all length of each of said radiating elements including the exposed portion of said central conductor and the over-all length of the shell being substantially equal to a quarter of the length of the operating wave, the capacitive reactance C of said exposed portion and the inductive reactance L of said shell portion being so related that

$$\sqrt{\frac{L}{C}}$$

as nearly as possible approaches R , the radiation resistance of each component of said antenna, and means for maintaining radio frequency voltages on said conductors, the phase relation between the voltages on adjacent conductors being

$\frac{360}{N}$

electrical degrees.

3. An antenna system comprising a number N of radiating elements disposed radially about a central point in a common horizontal plane, each radiating element spaced substantially

$\frac{360}{N}$

degrees from adjacent radiating elements, each of said radiating elements comprising a central cylindrical conductor element having a diameter which is a large fraction of the length of the op-

erating wave and an outer shell surrounding a portion of each of said conductors at their adjacent ends, said central conductor extending radially outward beyond the end of said outer shell, the over-all length of each of said radiating elements including the exposed portion of said central conductor and the over-all length of the shell being substantially equal to a quarter of the length of the operating wave, the capacitive reactance C of said exposed portion and the inductive reactance L of said shell portion being so related that

$$\sqrt{\frac{L}{C}}$$

as nearly as possible approaches R , the radiation resistance of each component of said antenna.

4. An antenna system comprising a number N of radiating elements disposed radially about a central point in a common horizontal plane, each radiating element spaced substantially

$\frac{360}{N}$

degrees from adjacent radiating elements, each of said radiating elements comprising a central cylindrical conductor element having a diameter which is a large fraction of the length of the operating wave and an outer shell surrounding a portion of each of said conductors at their adjacent ends, said central conductor extending radially outward beyond the end of said outer shell, the over-all length of each of said radiating elements including the exposed portion of said central conductor and the over-all length of the shell being substantially equal to a quarter of the length of the operating wave, the capacitive reactance C of said exposed portion and the inductive reactance L of said shell portion being so related that

$$\sqrt{\frac{L}{C}}$$

as nearly as possible approaches R , the radiation resistance of each component of said antenna, and means for maintaining radio frequency voltages on said radiating elements, the phase relation between the voltages on adjacent radiating elements being

$\frac{360}{N}$

electrical degrees.

5. An antenna system comprising a central conductor element having a transverse dimension which is a large fraction of the length of the operating wave and an outer shell surrounding a portion of said conductor, said central conductor extending beyond the end of said outer shell, the overall length of said shell and the exposed portion of said central conductor being substantially equal to one quarter the length of the operating wave, the capacitive reactance C of said extending portion and the inductive reactance L of said shell portion being so related that

$$\sqrt{\frac{L}{C}}$$

as nearly as possible approaches R , the radiation resistance of each component of said antenna.

6. An antenna system comprising a number N of radiating elements disposed radially about a

central point in a common horizontal plane, each radiating element spaced substantially

$$\frac{360}{N}$$

degrees from adjacent radiating elements, each of said radiating elements comprising a cylindrical conductor element and an outer shell surrounding a portion of each of said conductor elements at their adjacent ends, said central conductor extending radially outward beyond the end of said outer shell, the over-all length of each of said radiating elements including the exposed portion of said central conductor and the over-all length of the shell being substantially equal to a quarter of the length of the operating wave, the capacitive reactance C of said exposed portion and the inductive reactance L of said shell portion being so related that

$$\sqrt{\frac{L}{C}}$$

as nearly as possible approaches R, the radiation resistance of each radiating element of said antenna, each radiating element having a diameter which is large in terms of the length of the operating wave near the center of said antenna and which decreases along the length of said radiating element with increasing distance from said center.

7. An antenna system comprising a number N of radiating elements disposed radially about a central point in a common horizontal plane, each radiating element spaced substantially

$$\frac{360}{N}$$

degrees from adjacent radiating elements, each of said radiating elements comprising a cylindrical conductor element and an outer shell surrounding a portion of each of said conductor elements at their adjacent ends, said central conductor extending radially outward beyond the end of said outer shell, the over-all length of each of said radiating elements including the exposed portion of said central conductor and the over-all length of the shell being substantially equal to a quarter of the length of the operating wave, the capacitive reactance C of said exposed portion and the inductive reactance L of said shell portion being so related that

$$\sqrt{\frac{L}{C}}$$

as nearly as possible approaches R, the radiation resistance of each radiating element of said antenna, each radiating element having a diameter which is large in terms of the length of the operating wave near the center of said antenna and which decreases along the length of said radiating element with increasing distance from said center, and means for maintaining radio frequency voltages on said radiating elements, the phase relation between the voltages on adjacent radiating elements being

$$\frac{360}{N}$$

electrical degrees.

8. An antenna system comprising four radiating elements disposed radially about a central point in a common horizontal plane, each radiating element spaced substantially 90 degrees from adjacent radiating elements, each of said radiating elements comprising a conductor having a circular cross-section and an outer shell surround-

ing a portion of each of said conductors at their adjacent ends, said central conductor extending radially outward beyond the end of said outer shell, the over-all length of each of said radiating elements including the exposed portion of said central conductor and the over-all length of the shell being substantially equal to a quarter of the length of the operating wave, the capacitive reactance C of said exposed portion and the inductive reactance L of said shell portion being so related that

$$\sqrt{\frac{L}{C}}$$

15 as nearly as possible approaches R, the radiation resistance of each of said radiating elements, each radiating element having a diameter which is large in terms of the length of the operating wave near the center of said antenna and which decreases along the length of said conductor with increasing distance from said center, and means for maintaining radio frequency voltages on said radiating elements, the phase relation between the voltage on adjacent radiating elements being 90 electrical degrees.

9. An antenna system comprising a quarter wave aerial conductor element having a transverse dimension which is a large fraction of the length of the operating wave near the neutral

30 voltage plane of said antenna and decreases along the length of said conductor with increasing distance from said plane, a concentric conductor transmission line and means for coupling said line to said conductor element comprising a 35 tapered concentric conductor section having a central conductor and an outer shell surrounding said conductor, the ratio of the diameter of said conductor and shell being constant through the length of said tapered section whereby a gradual 40 transition between said transmission line and said antenna is attained without material change in the line surge impedance.

10. An antenna system comprising a number N of quarter wave aerial conductor elements having lateral dimensions which are large in terms of the length of the operating wave and disposed radially about a central point and in a common horizontal plane, each conductor spaced substantially

50

$$\frac{360}{N}$$

degrees from adjacent conductors and means for maintaining radio frequency voltages on said conductors, the phase relation between the voltages on adjacent conductors being

$$\frac{360}{N}$$

60 electrical degrees, said means comprising a concentric conductor transmission line and means for coupling said line to each of said conductor elements comprising a number N of tapered concentric conductor sections, each having a central conductor expanding into said aerial conductor

65 elements and an outer shell surrounding said conductor, the ratio of the diameter of said conductor and shell being constant through the length of said tapered section whereby a gradual transition between said transmission line and said antenna is attained without material change in the line surge impedance.

11. An antenna system comprising a number N of quarter wave aerial conductor elements having a circular cross section and disposed radially about a central point in a common horizontal

75

plane, each conductor having a diameter which is large in terms of the length of the operating wave near the center of said antenna and which decreases along the length of said conductor with increasing distance from said center, each conductor being spaced substantially

$$\frac{360}{N}$$

degrees from adjacent conductors and means for maintaining radio frequency voltages on said conductors, the phase relation between the voltages on adjacent conductors being

$$\frac{360}{N}$$

electrical degrees, said means comprising a concentric conductor transmission line and means for coupling said line to each of said conductor elements comprising tapered concentric conductor sections each having a central conductor of the same diameter as the conductor of the concentric line to which it is connected and an outer shell surrounding said conductor, the ratio of the diameter of each of said conductors and shells being constant through the length of said tapered sections whereby a gradual transition between said transmission line and said antenna is attained without material change in the line surge impedance.

12. An antenna system comprising four quarter wave conductor elements disposed radially about a central point and in a common horizontal plane, each conductor spaced substantially 90 degrees from adjacent conductors, each conductor having a diameter which is large in terms of the length of the operating wave near the center of said antenna and which decreases along the length of said conductor with increasing distance from said center and means for maintaining radio frequency voltages on said conductors, the phase relation between the voltages on adjacent conductors being equal to 90 electrical degrees, said means comprising a concentric conductor transmission line and means for coupling said line to each of said conductor elements comprising tapered concentric conductor sections, each having a central conductor of the same diameter as the conductor of the concentric line to which it is connected and an outer shell surrounding said conductor, the ratio of the diameter of said conductor and shell being constant through the length of said tapered section whereby a gradual transition between said transmission line and said antenna is attained without material change in the line surge impedance.

13. An antenna system comprising four quarter wave conductor elements disposed radially about a central point and in a common horizontal plane, each conductor spaced substantially 90 degrees from adjacent conductors and means for maintaining radio frequency voltages on said conductors, the phase relation between the voltages on adjacent conductors being equal to 90 electrical degrees and a reflector parallel to said plane and spaced therefrom a distance the order of a half wave length whereby maximum cancellation occurs between the wave radiated from said conductors in a direction away from said reflector and the wave reflected from said reflector.

14. An antenna system comprising a number N of quarter wave conductor elements disposed radially about a central point and in a common

horizontal plane each conductor spaced substantially

$$\frac{360}{N}$$

5 degrees from adjacent conductors and means for maintaining the radio frequency voltages on said conductors, the phase relation between the voltages on adjacent conductors being equal to

10

$$\frac{360}{N}$$

electrical degrees and a reflector parallel to said common horizontal plane and spaced therefrom a distance the order of a half wave length whereby maximum cancellation occurs between the wave radiated from said conductors in a direction away from said reflector and the wave reflected from said reflector.

15

15. An antenna system comprising four quarter wave conductor elements disposed radially about a central point and in a common horizontal plane, each conductor spaced substantially 90 degrees from adjacent conductors, each conductor having a diameter which is large in terms of the length of the operating wave near the center of said antenna and which decreases along the length of said conductor with increasing distance from said center and means for maintaining radio frequency voltages on said conductors, the phase relation between the voltages on adjacent conductors being equal to 90 electrical degrees, said means comprising a concentric conductor transmission line and means for coupling said line to each of said conductor elements comprising tapered concentric conductor sections, each having a central conductor of the same diameter as the conductor of the concentric line to which it is connected and an outer shell surrounding said conductor, the ratio of the diameter of said conductor and shell being constant through the length of said tapered section whereby a gradual transition between said transmission line and said antenna is attained without material change in the line surge impedance, and a reflector parallel to said plane and spaced therefrom a distance the order of a half wave length whereby maximum cancellation occurs between the wave radiated from said conductors in a direction away from said reflector and the wave reflected from said reflector.

20

20. An antenna system comprising four quarter wave conductor elements disposed radially about a central point and in a common horizontal plane, each conductor spaced substantially 90 degrees from adjacent conductors, each conductor having a diameter which is large in terms of the length of the operating wave near the center of said antenna and which decreases along the length of said conductor with increasing distance from said center and means for maintaining radio frequency voltages on said conductors, the phase relation between the voltages on adjacent conductors being equal to 90 electrical degrees, said means comprising a concentric conductor transmission line and means for coupling said line to each of said conductor elements comprising tapered concentric conductor sections, each having a central conductor of the same diameter as the conductor of the concentric line to which it is connected and an outer shell surrounding said conductor, the ratio of the diameter of said conductor and shell being constant through the length of said tapered section whereby a gradual transition between said transmission line and said antenna is attained without material change in the line surge impedance, and a reflector parallel to said plane and spaced therefrom a distance the order of a half wave length whereby maximum cancellation occurs between the wave radiated from said conductors in a direction away from said reflector and the wave reflected from said reflector.

25

25. An antenna system comprising a central conductor and an outer shell surrounding said conductor, said central conductor extending beyond the end of said outer shell, a concentric cable transmission line connected to said conductor and shell and forming a continuation thereof and means forming a neutral voltage plane at the junction of said shell with said line, the transverse dimension of said central conductor being large in terms of the length of the operating wave at the neutral plane and decreasing along the length of said antenna with increasing distance from said plane, and a conductive support connected between the end of said central conductor and said outer shell, said connection acting as an inductance connected between said conductor and said shell.

30

30. An antenna system comprising a central conductor and an outer shell surrounding said conductor, said central conductor extending beyond the end of said outer shell, a concentric cable transmission line connected to said conductor and shell and forming a continuation thereof and means forming a neutral voltage plane at the junction of said shell with said line,

the transverse dimension of said central conductor being large in terms of the length of the operating wave at the neutral plane and decreasing along the length of said antenna with increasing distance from said plane, and a conductive support connected between the end of said central conductor and said outer shell, said connection acting as an inductance connected between said conductor and said shell, and means for compensating for said inductance comprising an additional capacity connected between the central conductor and the outer shell at the point where the central conductor leaves the shell.

18. An antenna system comprising a plurality of radiating elements disposed radially in a common plane about a central neutral point, each of said elements formed of a central conductor having a transverse dimension large in terms of the length of the operating wave, and an outer shell surrounding said conductor, said central conductor extending beyond the end of said shell, a concentric cable transmission line and means for coupling said line at said central point to each of said elements, said means comprising a tapered concentric conductor section having a central conductor and an outer shell surrounding said conductor, the ratio of the diameter of said conductor and shell being constant through the length of said outer section whereby a gradual transition between said transmission line and said antenna is attained without material change in the line surge impedance.

19. An antenna system comprising a plurality of radiating elements disposed radially in a common plane about a central neutral point, each of said elements formed of a central conductor having a transverse dimension large in terms of the length of the operating wave, and an outer shell surrounding said conductor, said central conductor extending beyond the end of said shell, a concentric cable transmission line and means within said outer shell for coupling said line at said central point to each of said elements, said means comprising a tapered conductor connected to said central conductor and the ratio of the diameters of said tapered conductor and the interior of said shell being constant through their length whereby a gradual transition between said transmission line and said antenna is attained without material change in the line surge impedance, and a conductive support connected between the central conductor and the shell of each of said radiating elements, said connection acting as an inductance connected therebetween.

20. An antenna system comprising a number N of radiating elements disposed radially in a common plane about a central neutral point, each of said elements formed of a central conductor having a transverse dimension large in terms of the length of the operating wave, and an outer shell surrounding said conductor, said central conductor extending beyond the end of said shell, each conductor spaced

$$\frac{360}{N}$$

degrees from adjacent conductors and means for maintaining radio frequency voltages on said conductors, the phase relation between the voltages on adjacent conductors being equal to

$$\frac{360}{N}$$

electrical degrees, said means comprising a concentric cable transmission line and means within said outer shell for coupling said line at said

central point to each of said elements, said means comprising a tapered conductor connected to said central conductor, the ratio of the diameters of said tapered conductor and the interior of said outer shell being constant through their length whereby a gradual transition between said transmission line and said antenna is attained without material change in the line surge impedance, and a conductive support connected between the central conductor and the shell of each of said radiating elements, said connection acting as an inductance connected therebetween, and capacitive means connected between the elements of said coupling means for compensating for said increase in inductance.

21. An antenna system comprising a plurality of radiating elements each of said elements having a transverse dimension large in terms of the length of the operating wave and disposed radially in a common plane about a central neutral point, each of said elements formed of a central conductor and an outer shell surrounding said conductor, said central conductor extending beyond the end of said shell, and a conductive support connected between the end of said central conductor and said shell of each of said radiating elements, said connection acting as an inductance connected therebetween, a concentric cable transmission line and means for coupling said line at said central point to each of said elements within said outer shell, said means comprising a tapered conductor connected to said central conductor, the ratio of the diameters of the tapered conductor and the interior of the outer shell increasing along the length of said means whereby the increase in inductance caused by said conductive support is compensated.

22. An antenna system comprising a plurality of ellipsoidal radiating elements disposed radially in a common plane about a central neutral point, each of said elements formed of a central conductor having a transverse dimension large in terms of the length of the operating wave, and an outer shell surrounding said conductor, said central conductor extending beyond the end of said shell, a concentric cable transmission line and means for coupling said line at said central point to each of said elements, said means comprising a tapered concentric conductor section having a central conductor and an outer shell surrounding said conductor, the ratio of the diameter of said conductor and shell being constant through the length of said outer section whereby a gradual transition between said transmission line and said antenna is attained without material change in the line surge impedance.

23. An antenna system comprising a plurality of ellipsoidal radiating elements disposed radially in a common plane about a central point, each of said elements formed of a central conductor having a transverse dimension large in terms of the length of the operating wave and an outer shell surrounding said conductor, said central conductor extending beyond the end of said shell, a concentric cable transmission line and means within said outer shell for coupling said line at said central point to each of said elements, said means comprising a tapered conductor connected to said central conductor, the ratio of the diameters of said tapered conductor and the interior of said shell being constant through their length whereby a gradual transition between said transmission line and said antenna is attained without material change in the line surge impedance, and a conductive support connected between the cen-

tral conductor and the shell of each of said radiating elements, said connection acting as an inductance connected therebetween.

24. An antenna system comprising a number N of ellipsoidal radiating elements disposed radially in a common plane about a central neutral point, having a transverse dimension large in terms of the length of the operating wave, and an outer shell surrounding said conductor, said central conductor extending beyond the end of said shell, each conductor spaced

$$\frac{360}{N}$$

degrees from adjacent conductors and means for maintaining radio frequency voltages on said conductors, the phase relation between the voltages on adjacent conductors being equal to

$$\frac{360}{N}$$

electrical degrees, said means comprising a concentric cable transmission line and means within said outer shell for coupling said line at said central point to each of said elements, said means comprising a tapered conductor connected to said central conductor, the ratio of the diameters of said tapered conductor and the interior of said outer shell being constant through their length whereby a gradual transition between said transmission line and said antenna is attained without material change in the line surge impedance, and a conductive support connected between the central conductor and the shell of each of said radiating elements, said connection acting as an inductance connected therebetween, and capacitive means connected between the elements of said coupling means for compensating for said increase in inductance.

25. An antenna system comprising a plurality of ellipsoidal radiating elements each of said elements having a transverse dimension large in terms of the length of the operating wave and disposed radially in a common plane about a central neutral point, each of said elements formed of a central conductor and an outer shell surrounding said conductor, said central conductor extending beyond the end of said shell, and a conductive support connected between the end of said central conductor and said shell of each of said radiating elements, said connection acting as an inductance connected therebetween, a concentric cable transmission line and means within said outer shell for coupling said line at said central point to each of said elements, said means comprising a tapered conductor connected to said central conductors, the ratio of the diameters of the tapered conductor and the interior of the outer shell increasing along the length of said means whereby the increase in inductance caused by said conductive support is compensated.

26. An antenna system comprising a plurality of antennas each including a number N of quarter wave conductor elements having lateral dimensions which are large in terms of the length of the operating wave and disposed radially about a central point in a common plane, each conductor spaced substantially

$$\frac{360}{N}$$

degrees from adjacent conductors and means for maintaining radio frequency voltages on said

conductors, the phase relation between the voltages on adjacent conductors being

$$\frac{360}{N}$$

electrical degrees, said antennas being located in parallel planes and having their central points on a common axis perpendicular to said planes, the corresponding conductor elements of adjacent antennas being so energized from separate energy sources for each antenna that opposing phase rotations are obtained.

27. An antenna system comprising a plurality of antennas each including a number N of quarter wave cylindrical conductor elements having a diameter which is large in terms of the length of the operating wave and disposed radially about a central point in a common plane, each conductor spaced substantially

20

$$\frac{360}{N}$$

degrees from adjacent conductors, said antennas being located in parallel planes and having their central points on a common axis perpendicular to said planes, said antennas being energized in an in phase relationship.

25

28. An antenna system comprising a plurality of antennas each including a number N of quarter wave conductor elements having a circular cross-section and disposed radially about a central point in a common horizontal plane, each conductor having a diameter which is large in terms of the length of the operating wave near the center of said conductor and which decreases along the length of said conductor with increasing distance from said center, each conductor being spaced substantially

40

$$\frac{360}{N}$$

degrees from adjacent conductors, and means for maintaining radio frequency voltages on said conductors, the phase relation between the voltages on adjacent conductors being

45

$$\frac{360}{N}$$

electrical degrees, said antennas being located in parallel planes and having their central points on a common axis perpendicular to said planes, said antennas being energized in an opposing phase relationship.

50

29. An antenna system comprising a plurality of antennas as defined in claim 11, located in parallel planes and with their central points on a common axis perpendicular to said plane, said antennas being energized for opposing phase rotation from different energy sources.

55

30. An antenna system comprising a plurality of antennas as defined in claim 20, located in parallel planes and with their central points on a common axis perpendicular to said planes, said antennas being energized for opposing phase rotation from different energy sources.

60

31. An antenna system comprising a plurality of antennas as defined in claim 23, located in parallel planes and with their central points on a common axis perpendicular to said planes, said antennas being energized for opposing phase rotation from different energy sources.

65

32. An antenna system comprising a plurality of antennas each including a number N of quarter wave conductor elements having lateral dimensions which are large in terms of the length

70

of the operating wave and disposed radially about a central point in a common plane, each conductor being spaced substantially

$$\frac{360}{N}$$

degrees from adjacent conductors, and means for maintaining radio frequency voltages on said conductors, the phase relation between the voltages on adjacent conductors being

$$\frac{360}{N}$$

electrical degrees, said antennas being located in parallel planes and having their central points on a common axis perpendicular to said planes, said antennas being so energized from separate energy sources for each antenna that opposing phase rotations are obtained, the elements of one antenna being arranged to bisect the projected angles formed by the elements of the adjacent antenna.

33. An antenna system comprising a plurality of antennas each including a number N of quarter wave cylindrical conductor elements having a diameter which is large in terms of the length of the operating wave and disposed radially about a central point in a common horizontal plane, each conductor being spaced substantially

$$\frac{360}{N}$$

degrees from adjacent conductors, and means for maintaining radio frequency voltages on said conductors, the phase relation between the voltages on adjacent conductors being

$$\frac{360}{N}$$

electrical degrees, said antennas being located in parallel planes and having their central points on a common axis perpendicular to said planes, said antennas being so energized from separate energy sources for each antenna that opposing phase rotations are obtained, the elements of one antenna being arranged to bisect the projected angles formed by the elements of the adjacent antenna.

34. An antenna system comprising a plurality of antennas each including a number N of quarter wave conductor elements having a circular cross-section and disposed radially about a central point in a common horizontal plane, each conductor element having a diameter which is large in terms of the length of the operating wave near the center of said antenna and which decreases along the length of said conductor with increasing distance from said center, each conductor being spaced substantially

$$\frac{360}{N}$$

degrees from adjacent conductors, and means for maintaining radio frequency voltages on the conductors of each of said antennas, the phase relation between the voltages on adjacent conductors being

$$\frac{360}{N}$$

electrical degrees, said antennas being located in parallel planes and having their central point on a common axis perpendicular to said planes, said antennas being energized for opposing phase rotation from separate energy sources, the elements of one antenna being arranged to bisect the projected angles formed by the elements of the adjacent antenna.

35. An antenna system comprising a plurality of antennas as defined in claim 11, located in parallel planes and with their central points on a common axis perpendicular to said planes, the elements of one antenna arranged to bisect the projected angles formed by the elements of the other antenna.

5 36. An antenna system comprising a plurality of antennas as defined in claim 20, located in parallel planes and with their central points on a common axis perpendicular to said planes, the elements of one antenna arranged to bisect the projected angles formed by the elements of the other antenna.

10 37. An antenna system comprising a plurality of antennas as defined in claim 23, located in parallel planes and with their central points on a common axis perpendicular to said planes, the elements of one antenna arranged to bisect the projected angles formed by the elements of the other antenna.

15 38. A horizontal loop antenna comprising four dipole antennae forming a circle, each dipole comprising a pair of conductors arranged in closely spaced parallel planes and each bent in an arc of a circle, means for connecting the conductors of each dipole together at their extreme ends, one conductor of each pair being broken at its mid point forming a pair of adjacent ends, a concentric cable transmission line and means for connecting the central conductor of said line to one of the adjacent ends of each dipole and means for connecting the casing of said transmission line to the other of the adjacent ends of each dipole antenna.

20 39. A television antenna system for simultaneous transmission of video and audio signals on closely adjacent frequencies without interference comprising a turnstile antenna energized by one of said signals and a loop antenna energized by the other of said signals, said antennas being located in parallel horizontal planes, and means for supporting said antennas with their central points on a common axis perpendicular to said planes.

40 40. An antenna system for simultaneous transmission of a pair of signals on closely adjacent frequencies without interference comprising a turnstile antenna comprising a number N of quarter wave conductor elements having lateral dimensions which are large in terms of the length of the operating wave and disposed radially about a central point in a common horizontal plane, each conductor spaced substantially

$$\frac{360}{N}$$

60 degrees from adjacent conductors, and means for maintaining radio frequency voltages on said conductors representative of one of said signals, the phase relation between the voltages on adjacent conductors being

65

$$\frac{360}{N}$$

electrical degrees, and a loop antenna energized by the other of said signals comprising four dipole antennae forming a circle, each dipole comprising a pair of conductors arranged in closely spaced parallel planes and each bent in an arc of a circle, means for connecting the conductors of each dipole together at their extreme ends, one conductor of each pair being broken at its mid point forming a pair of adjacent ends, a concentric cable transmission line and means for connecting the central conductor of said line to one of the adjacent ends of each dipole and means for connecting the casing of said transmission line to the other of the adjacent ends of each dipole antenna.

mid point forming a pair of adjacent ends, a concentric cable transmission line and means for connecting the central conductor of said line to one of the adjacent ends of each dipole and means for connecting the casing of said transmission line to the other of the adjacent ends of each dipole antenna, said antennas being located in parallel horizontal planes, and means for supporting said antennas with their central points on a common axis perpendicular to said planes.

41. An antenna system for simultaneous transmission of a pair of signals on closely adjacent frequencies without interference comprising a turnstile antenna comprising a number N of quarter wave conductor elements having a circular cross section and disposed radially about a central point in a common horizontal plane, each conductor having a diameter which is large in terms of the length of the operating wave near the center of said antenna and which decreases along the length of said conductor with increasing distance from said center, each conductor being spaced substantially

$$\frac{360}{N}$$

degrees from adjacent conductors and means for maintaining radio frequency voltages on said conductors representative of one of said signals, the phase relation between the voltages on adjacent conductors being

$$\frac{360}{N}$$

electrical degrees, said means comprising a concentric conductor transmission line and means for coupling said line to each of said conductor elements comprising tapered concentric conductor sections, each having a central conductor and an outer shell surrounding said conductor, the ratio of the diameter of each of said conductors and shells being constant through the length of said tapered sections whereby a gradual transition between said transmission line and said antenna is attained without material change in the line surge impedance, and a loop antenna energized by the other of said signals comprising four dipole antennae forming a circle, each dipole comprising a pair of conductors arranged in closely spaced parallel planes and each bent in an arc of a circle, means for connecting the conductors of each dipole together at their extreme ends, one conductor of each pair being broken at its mid point forming a pair of adjacent ends, a concentric cable transmission line and means for connecting the central conductor of said line to one of the adjacent ends of each dipole and means for connecting the casing of said transmission line to the other of the adjacent ends of each dipole antenna, said antennas being located in parallel horizontal planes, and means for supporting said antennas with their central points on a common axis perpendicular to said planes.

42. An antenna system for simultaneous transmission of a pair of signals on closely adjacent frequencies without interference comprising a turnstile antenna comprising a number N of radiating elements disposed radially in a common plane about a central neutral point, each of said elements formed of a central conductor having a transverse dimension large in terms of the length of the operating wave, and an outer shell surrounding said conductor, said central con-

ductor extending beyond the end of said shell, each conductor spaced

$$\frac{360}{N}$$

degrees from adjacent conductors and means for maintaining radio frequency voltages on said conductors representative of one of said signals, the phase relation between the voltages on adjacent conductors being equal to

$$\frac{360}{N}$$

electrical degrees, said means comprising a concentric cable transmission line and means within said outer shell for coupling said line at said central point to each of said elements comprising a tapered conductor connected to said central conductor, the ratio of the diameters of said tapered conductor and the interior of said outer shell being constant through their length whereby a gradual transition between said transmission line and said antenna is attained without material change in the line surge impedance,

25 and a conductive support connected between the central conductor and the shell of each of said radiating elements, said connection acting as an inductance connected therebetween, and capacitive means connected between the elements of said coupling means for compensating for said increase in inductance, and a loop antenna energized by the other of said signals comprising four dipole antennae forming a circle, each dipole comprising a pair of conductors arranged

30 in closely spaced parallel planes and each bent in an arc of a circle, means for connecting the conductors of each dipole together at their extreme ends, one conductor of each pair being broken at its mid point forming a pair of adjacent ends, a concentric cable transmission line and means for connecting the central conductor of said line to one of the adjacent ends of each dipole and means for connecting the casing of said transmission line to the other of the adjacent ends of each dipole antenna, said antennas being located in parallel horizontal planes, and means for supporting said antennas with their central points on a common axis perpendicular to said planes.

45 50 55 60 65 70 75 43. An antenna system for simultaneous transmission of a pair of signals on closely adjacent frequencies without interference comprising a turnstile antenna energized by one of said signals comprising a plurality of ellipsoidal radiating elements disposed radially in a common plane about a central point, each of said elements formed of a central conductor having a transverse dimension large in terms of the length of the operating wave and an outer shell surrounding said conductor, said central conductor extending beyond the end of said shell, a concentric cable transmission line and means within said outer shell for coupling said line at said central point to each of said elements comprising a tapered conductor connected to said central conductor,

the ratio of the diameters of said tapered conductor and the interior of said shell being constant through their length whereby a gradual transition between said transmission line and said antenna is attained without material change in the line surge impedance, and a conductive support connected between the central conductor and the shell of each of said radiating elements, said connection acting as an inductance connected therebetween, and a loop antenna ener-

gized by the other of said signals comprising four dipole antennae forming a circle, each dipole comprising a pair of conductors arranged in closely spaced parallel planes and each bent in an arc of a circle, means for connecting the conductors of each dipole together at their extreme ends, one conductor of each pair being broken at its mid point forming a pair of adjacent ends, a concentric cable transmission line and means for connecting the central conductor of said line to one of the adjacent ends of each dipole and means for connecting the casing of said transmission line to the other of the adjacent ends of each dipole antenna, said antennas being located in parallel horizontal planes, and means for supporting said antennas with their central points on a common axis perpendicular to said planes.

44. An antenna system for simultaneous transmission of a pair of signals on closely adjacent frequencies without interference comprising a turnstile antenna comprising a number N of ellipsoidal radiating elements disposed radially in a common plane about a central neutral point, having a transverse dimension large in terms of the length of the operating wave, and an outer shell surrounding said conductor, said central conductor extending beyond the end of said shell, each conductor spaced

$$\frac{360}{N}$$

degrees from adjacent conductors and means for maintaining radio frequency voltages on said conductors representative of one of said signals, the phase relation between the voltages on adjacent conductors being equal to

$$\frac{360}{N}$$

electrical degrees, said means comprising a concentric cable transmission line and means within said outer shell for coupling said line at said central point to each of said elements comprising a tapered conductor connected to said central conductor, the ratio of the diameters of said tapered conductor and the interior of said outer shell being constant through their length whereby a gradual transition between said transmission line and said antenna is attained without material change in the line surge impedance, and a conductive support connected between the central conductor and the shell of each of said radiating elements, said connection acting as an inductance connected therebetween, capacitive means connected between the elements of said coupling means for compensating for said increase in inductance, and a loop antenna energized by the other of said signals comprising four dipole antennae forming a circle, each dipole comprising a pair of conductors arranged in closely spaced parallel planes and each bent in an arc of a circle, means for connecting the conductors of each dipole together at their extreme ends, one conductor of each pair being broken at its mid point forming a pair of adjacent ends, a concentric cable transmission line and means for connecting the central conductor of said line to one of the adjacent ends of each dipole and means for connecting the casing of said transmission line to the other of the adjacent ends of each dipole antenna, said antennas being located in parallel horizontal planes and with their central points on a common axis perpendicular to said planes.

45. An antenna system for simultaneous transmission of a pair of signals on closely adjacent frequencies without interference comprising a turnstile antenna comprising a number N of ellipsoidal radiating elements disposed radially in a common plane about a central neutral point, having a transverse dimension large in terms of the length of the operating wave, and an outer shell surrounding said conductor, said central conductor extending beyond the end of said shell, the capacitative reactance C of said extending portion and the inductive reactance L of said shell portion being so related that

$$\sqrt{\frac{L}{C}}$$

as nearly as possible approaches R , the radiation resistance of each component of said antenna, each conductor spaced

$$\frac{360}{N}$$

degrees from adjacent conductors and means for maintaining radio frequency voltages on said conductors representative of one of said signals, the phase relation between the voltages on adjacent conductors being equal to

$$\frac{360}{N}$$

30 electrical degrees, said means comprising a concentric cable transmission line and means within said outer shell for coupling said line at said central point to each of said elements comprising a tapered conductor connected to said central conductor, the ratio of the diameters of said tapered conductor and the interior of said outer shell being constant through their length whereby a gradual transition between said transmission line and said antenna is attained without material change in the line surge impedance, and a conductive support connected between the central conductor and the shell of each of said radiating elements, said connection acting as an inductance connected therebetween, capacitive means connected between the elements of said coupling means for compensating for said increase in inductance, and a loop antenna energized by the other of said signals comprising four dipole antennae forming a circle, each dipole comprising a pair of conductors arranged in closely spaced parallel planes and each bent in an arc of a circle, means for connecting the conductors of each dipole together at their extreme ends, one conductor of each pair being broken at its midpoint forming a pair of adjacent ends, a concentric cable transmission line and means for connecting the central conductor of said line to one of the adjacent ends of each dipole and means for connecting the casing of said transmission line to the other of the adjacent ends of each dipole antenna, said antennas being located in parallel horizontal planes and with their central points on a common axis perpendicular to said planes.

46. A short wave antenna and transmission line having a wide band impedance versus frequency characteristic comprising a plurality of conductive structures in the form of elongated surfaces of revolution, each of said structures having at least one end of small diameter and a coaxial transmission line for each said structures, the inner conductor of each line gradually expanding in diameter until it imperceptibly merges with the small diameter end of its associated structure, the outer conductor of each transmission line also expanding in diameter at the loca-

tion of expansion of the inner conductor thereof to maintain substantially constant the outer to inner diameter ratio between the conductors.

47. An antenna and transmission line in accordance with claim 46, characterized in this that each outer conductor increases in diameter and extends, for a short distance at least, beyond the small diameter end of the conductive structure with which it is associated to surround a portion thereof, said outer conductor being flared at its open end.

48. A short wave antenna and transmission line in accordance with claim 46, characterized in this that said conductive structures are arranged in paired relationship with the longitudinal axes of each pair in substantially the same straight line, the conductors of said transmission lines extending substantially perpendicular to said line.

49. A short wave antenna and transmission line system comprising a conductive structure in the form of an elongated surface of revolution having at least one end of small diameter extending from an electrically conducting surface such that the longitudinal axis of said structure is substantially perpendicular to said surface and the small diameter end is adjacent to said surface, a coaxial transmission line connected to the small diameter end of said structure, the inner conductor of said line gradually expanding in diameter until it imperceptibly merges with the small diameter end of said structure, the outer conductor of said line also expanding in diameter at the location of expansion of the inner conductor.

50. A short wave antenna and transmission line system comprising an antenna element which gradually expands for at least a portion of its length and connected thereto a coaxial transmission line, said line having a gradually expanding inner conductor and a gradually expanding outer shell, the diameter of the inner conductor of said transmission line gradually merging with the gradually expanding antenna element.

51. A horizontal loop antenna comprising a plurality of dipole antennae forming a closed ge-

ometrical figure, each dipole comprising a pair of conductors arranged in closely spaced parallel planes, means for connecting the conductors of each dipole together at their extreme ends, 5 connecting means of adjacent dipoles being closely adjacent, one conductor of each pair being broken at its midpoint forming a pair of adjacent ends and energizing means connected to each of said pair of adjacent ends.

52. A horizontal loop antenna comprising a plurality of dipole antennae forming a closed geometrical figure, each dipole comprising a pair of conductors arranged in closely spaced parallel planes, means for connecting the conductors of each dipole together at their extreme ends, one conductor of each pair being broken at its midpoint forming a pair of adjacent ends and energizing means connected to each of said pair of adjacent ends, the other of said conductors of each pair being grounded at its midpoint.

53. A horizontal loop antenna comprising a plurality of dipole antennae forming a closed geometrical figure, each dipole comprising a pair of conductors arranged in closely spaced parallel planes, the length of each conductor being of the order of a quarter of the operating wave, means for connecting the conductors of each dipole together at their extreme ends, the connecting means of adjacent dipoles being closely adjacent, one conductor of each pair being broken at its midpoint forming a pair of adjacent ends, the said pairs of adjacent ends of each dipole being connected in parallel to a source of oscillations.

54. A radiating element for an antenna system comprising a pair of conductors arranged in closely spaced parallel planes and connected together at their extreme ends, one of said conductors being discontinuous at its midpoint forming a pair of adjacent ends, means for energizing said element connected to said pair of adjacent ends, the other of said conductors being grounded at its midpoint.

NILS E. LINDENBLAD.
